UNITED STATES PATENT OFFICE.

GUSTAF ALEXANDER JOHNSON, OF ST. CHARLES, ILLINOIS.

CORE-SETTER.

SPECIFICATION forming part of Letters Patent No. 716,237, dated December 16, 1902.

Application filed April 14, 1902. Serial No. 102,803. (No model.)

To all whom it may concern:

Be it known that I, GUSTAF ALEXANDER JOHNSON, a citizen of the United States, residing at St. Charles, in the county of Kane 5 and State of Illinois, have invented a certain new and useful Improvement in Core-Setters, of which the following is a specification.

My invention relates to machines or devices for placing cores. It is illustrated in the accompanying drawings, wherein—

Figure 1 is a plan view of my apparatus. Fig. 2 is a plan view of the drag with my apparatus removed. Fig. 3 is an end view. Fig. 4 is a cross-section on the line 4-4 of Fig. 1. Fig. 5 is a detail of the movable shield. Fig. 6 is a detail of the core-holder.

Like parts are indicated by the same letter in all the figures.

A is the drag or lower portion of the flask. B is a frame having at each end a projecting alinement device B', which co-operates with the upwardly-projecting alinement device B² on the drag. The case B is provided with two rollers B³ B³, although there may be 20 any convenient number of rollers. They are journaled at B⁴ B⁴, so as to rotate freely in either direction. Each roller is provided with a longitudinal slot B⁵, and it may have more than one such slot, if desired. On the frame 25 A rises the side bars C C, connected in front by the cross-piece C'. Thus there is made a sort of upper frame inclosed by the bars and cross-pieces C C and C'. The space between these bars is floored by the part D, which is arranged, as indicated in Fig. 4, in long trough-like bodies. In the bottom of the trough lies 30 one of the rollers. The slot in the bottom of the trough is just filled with the roller, so that it is free to rotate; but the cores above 35 cannot drop out between the trough or bottom portion and the roller. Upwardly projecting from each roller at one end is an arm E, pivoted at E' to the bail E², which is provided with a handle E³. By moving this handle and bail it is evident the rollers may be 40 rocked back and forth.

F is a device in which a series of cores F' may be arranged. Its bottom portion is shaped so as to conform to the cross-section 45 configuration of the core case or holder. When the device is to be charged with cores,

such a holder as F, properly filled with cores, is set in position, as indicated at the lower part of Fig. 1. It will be observed that the part F² projects, and if now the bridge F³ be 55 placed in position, its projecting ears F⁴ F⁴ taking into the slots F⁵ F⁵, the core-holder F may be withdrawn, as indicated in Fig. 1, and the cores will be prevented from coming out with it, and by continuing this process 60 the result will be that the core-case will be completely charged with a series of sets of cores. Two of such sets are shown in Fig. 1.

G indicates the sand in the drag, and on its surface are arranged a series of pattern-prints G'. The object of my invention is to lay a series of these small cores in proper relation in these pattern-prints. Having done this my device is removed, and the upper portion of the flask is put into position, whereupon the metal can be run in. The object of the invention, therefore, is to obviate the delays, inaccuracies, expense, and hand-labor involved in setting in place a large number of relatively small cores. My invention is of 70 course applicable to other than cores exactly such as I have shown; but I am showing it in connection with the cores used in the manufacture of links for link belting as presenting an excellent illustration of the use of my 75 invention.

The separate cores J J are received into the slots B⁵ when the rollers are turned so as to bring that slot up into the core-chamber. If then the motion of the roller be reversed 85 or continued, so as to bring this slot beyond or outside of the bottom or floor of the core-case, the parts are so arranged that the little core will drop into the groove made in the pattern-print to receive it, as indicated in 90 Fig. 4. By having two rows of such pattern-prints on each side it is possible to lay an entire set of these cores in each of four rows of such pattern-prints by a single to-and-fro movement of the handle connected with 95 the two rollers. When the little cores are thus placed in position, the apparatus is removed and the upper portion of the flask can be put in place. By having the core-box substantially the same in form as the upper 100 portion of the flask and using the same alinement devices the parts will always come into

proper position. A suitable core-case and core-setting apparatus will have to be adapted for each particular form or size of flask.

I have shown two of the slots B⁵B⁵ on each 5 roller, the idea being that one slot discharges on one side and the other on the other by partly rotating the roller. Of course it is evident that one slot may be made to serve the purpose of both; but in that event the roller 10 would have to rotate through a large arc.

The use and operation of my invention have been sufficiently shown in the preceding 15 description. It will be understood, however, that I do not wish to be limited to the precise 20 form and arrangement of parts shown, and some of the parts of my device are to be taken, in a sense, as diagrammatic, simply to illustrate its use, operation, and construction without confining myself to the particular 25 form, size, and shape of the parts shown.

The method of arranging the cores in rows and packing them in a core-box, as well as the device used for that purpose, can of course be greatly varied without departing from the 30 spirit of my invention.

The device F is intended to be used in transporting a group or roll of the cores to the machine or device for placing the cores, and after the cross or movable bridge piece 35 F⁸ has been placed in position the part F can be pulled out, whereupon the row or group of cores will be properly arranged in position for use. I have referred to this group or series of cores as F', meaning to indicate there- 40 by the entire group. The separate cores in the group I have indicated by the letters J J. The two slots in the roller will obviously discharge one on one side when the roller is slightly rocked in that direction and the other on the opposite side when the roller is slightly 45 rocked in that direction. The roller is a rocking and not a rotating roller, and when one slot is exposed to the cores to be filled thereby the other is below the bottom and is discharging its cores.

I claim—

1. In a core-setter the combination of a core-case adapted to hold a series of loose cores with a movable core-delivering device 50 mounted therein, and means for operating such core-delivering device to cause it to select, carry and deliver individual cores from the case to the pattern-print.

2. In a core-setter the combination of a core-case, having a trough-like bottom, with a movable core-discharging device mounted in such trough-like bottom, and means for moving it so that it will first take a core from the case and then deliver it to the pattern- 60 print.

3. In a core-setter the combination of a core-case with a trough-like bottom and a slotted roller mounted in such trough-like bottom, and means for rotating said roller so as 65 to bring the slot first above and then below the bottom.

4. In a core-setter the combination of a

core-case with a trough-like bottom and a slotted roller mounted in such trough-like bottom therein, and means for rotating said roller 70 so as to bring the slot first above and then below the bottom, and an alinement device to bring the core-case in proper relation to the pattern-print.

5. In a core-setter the combination of a 75 core-case with means for arranging the cores therein in a series of groups, a series of core-discharging devices mounted beneath such groups of cores, and means for rotating them so that they take cores from within the case 80 and deliver them outside the case to the pattern-print.

6. In a core-setter the combination of a core-case with means for arranging the cores therein in a series of groups, a series of core- 85 discharging devices mounted beneath such groups of cores, and means for rotating them so that they take cores from within the case and deliver them outside the case to the pattern-print, said means consisting of slotted 90 rollers in the bottom of the core-case.

7. In a core-setter the combination of a core-case with a movable bridge and a series of devices for holding said bridge whereby the cores may be arranged in groups in the case. 95

8. In a core-setter the combination of a core-case with a movable bridge and a series of devices for holding said bridge whereby the cores may be arranged in groups in the case, and a core-holder adapted to be moved 100 underneath said bridge to discharge the cores in groups back of the bridge.

9. In a core-setter the combination of a drag with alinement devices, and a core-case with corresponding alinement devices, a core- 105 discharging device mounted in the bottom of such core-case and adapted to receive the cores from the case and discharge them into the pattern-prints in the drag.

10. In a core-setter the combination of a 110 drag with alinement devices, and a core-case with corresponding alinement devices, a core-discharging device mounted in the bottom of such core-case and adapted to receive the cores from the case and discharge them into 115 the pattern-prints in the drag, said discharging device consisting of slotted rollers with means for rocking them.

11. In a core-setter the combination of a drag with alinement devices, and a core-case 120 with corresponding alinement devices, a core-discharging device in the bottom of such core-case and adapted to receive the cores from the case and discharge them into the pattern-prints in the drag, said discharging device 125 consisting of slotted rollers with means for rocking them, and the bottom of said case provided with a series of troughs each of which terminates in a roller.
